HYDRAULIC JACK

Joseph J. Mueller, Racine, Wis., assignor to
American Grinder and Specialty Corporation,
Milwaukee, Wis.

Application June 30, 1934, Serial No. 733,286

5 Claims. (Cl. 60—52)

This invention appertains to lifting devices, and more particularly to hydraulic jacks of the light portable type especially adapted for automobile use.

- 5 One of the salient objects of my invention is to generally improve the construction of hydraulic jacks, so as to produce an exceptionally simple and rugged structure, which can be manufactured and placed upon the market at a reasonable cost.
- 0 Another important object of my invention is to provide a novel jack base cast as a single unit, having formed directly thereon the cylinder for the pressure pump, the high pressure passageway being formed in the base in a novel manner, 5 whereby the perforation of the outer sides of the base is eliminated and thereby effectively forms a leak-proof structure.

A further object of my invention is the provision of novel means for forming the valves 0 separate from the pump cylinder, whereby the same will be readily accessible and easily removed for cleaning, etc.

With these and other objects in view, the invention consists in the novel construction, arrangement and formation of parts, as will be hereinafter more specifically described, claimed and illustrated in the accompanying drawings, in which drawings:—

Figure 1 is a side elevation of a jack constructed in accordance with my invention, parts of the same being shown broken away and in section to illustrate structural details.

Figure 2 is a detail vertical section through a slightly modified form of jack, the view being taken substantially on the line 2—2 of Figure 3.

Figure 3 is a horizontal section through the modified form of jack, taken substantially on the line 3—3 of Figure 2, looking in the direction of the arrows.

Referring to the drawings in detail, wherein similar reference characters designate corresponding parts throughout the several views, the letter A generally indicates my improved hydraulic jack, which comprises a base 5 cast as a single unit.

The base has formed centrally thereon the body portion 6, which is provided with the axially disposed recess 7 forming a part of the ram cylinder. The side wall of this recess is internally threaded for the reception of the removable ram cylinder proper 8.

The body 6 is preferably formed on a base plate 9, and suitable reinforcing ribs can extend from the plate 9 to the body. This plate 9 is so shaped as to permit the jack to be readily slid

over the ground, and the same is of the sled type. At one side of the axial recess 7 I form a vertically disposed recess 11 in which is mounted the valves, as will be hereinafter more fully set forth. It is to be noted, however, that the side wall of recess 11 is provided with internal threads 12.

Extending laterally from the base body 6 and at an angle thereto is the pump cylinder 13, and this cylinder is cast integral with the base and forms a unit thereof. Reciprocally mounted in 10 the pump cylinder 13 is a plunger 14, and this plunger extends exteriorly of the cylinder through a packing gland 15.

Formed directly on the cylinder 13 is the up-standing supporting arm, or bracket, 16 to which 15 is pivotally secured, as at 17, the operating handle socket 18. The socket 18 is connected with the outer end of the plunger by the use of a suitable pin and slot connection 19. The inner end of the plunger can be provided with any preferred 20 type of pump washers 20.

Leading from the lower end of the pump cylinder 20 is a passageway 21 which connects with the valve recess 11. Communicating with the extreme lower end of the recess 7 is a diagonally 25 extending high pressure passageway 22, and this passageway 22 communicates with the valve cavity 11 by means of a relatively short high pressure passageway 23.

Communicating with the rear end of the high 30 pressure passageway 22 is a relief passageway, or by-pass conduit, 24, and this passageway 24 is extended to the upper end of the base body and communicates with the interior of the reservoir cylinder, as will be later described.

A pressure relief valve 25 is carried by the base and extends through a packing gland 26. The inner end of the relief valve normally seats on the walls of the passageway 22 for closing communication between the passageway 22 and the 40 relief, or by-pass, passageway 24.

As clearly shown in the drawings, the ram cylinder 8 extends a considerable distance above the base and above the reservoir cylinder 27. The reservoir cylinder 27 is snugly fitted within the 45 body portion 6 of the base, and this body portion is suitably rabbeted, or chamfered, to receive the same. A removable head 28 is provided for holding the reservoir cylinder in place, and the same is threaded on the upper end of the ram cylinder, 50 as at 29. An annular shoulder 30 is formed on the head for engagement with the upper end of the reservoir cylinder 27. Consequently, when the head is threaded in place the same snugly bears against the reservoir cylinder and forces 55

the same tightly on the base to form a leak-proof joint.

The ram 31 is slidably received within the ram cylinder and extends through a packing gland 32 on said head 28. The ram 31 adjustably carries the lifting head, or foot, 33. The inner end of the ram can be provided with any preferred type of pump washers 34.

Snugly fitted within the valve recess 11 is a valve cage 35. This cage carries a ball valve 36. A second valve cage 37 is threaded into the recess 11 and is tightly fitted on top of the cage 35 to hold the same in place. A ball valve 38 is carried by the cage 37.

It is to be noted that the valve cage 35 is provided with a longitudinally extending passageway 39 and a cross passageway 40 which opens out through the sides of the cage. By referring to the drawings, it can be seen that when the cages are in proper position, the passageway 21 communicates with the interior of the cage above the valve 36.

In operation of my improved jack, the lifting foot, or head, 33 is initially adjusted on the ram to the desired position, after which the pump is actuated. Upon the up-stroke of the pump, the oil, or other liquid, will be sucked into the pump cylinder from the reservoir past the valve 38, which is moved off its seat. The valve 36 is held on its seat during this movement of the plunger due to the suction created.

Upon downward movement of the pump plunger, the valve 38 is forced on its seat, and the valve 36 is moved off its seat, and consequently the fluid under pressure will flow through the passageway 21, the valve cage, and through the passageways 23 and 22, into the ram cylinder, causing upward movement of the ram. Obviously, the ram can be raised to any desired position by continued operation of the pump plunger.

When it is desired to release the ram and permit the lowering thereof, the release valve is unthreaded so as to move the same off its seat. Consequently, the liquid is permitted to flow through the passageways 22 and 24 back into the reservoir.

The reservoir cylinder 27, adjacent to its upper end, can be provided with a removable plug 41 so as to permit the desired quantity of oil, or other liquid, to be introduced into the reservoir.

From the foregoing description, it can be seen that an exceptionally simple and rugged structure is had and that all of the passageways are formed interiorly of the base without the necessity of drilling the base from the outer sides thereof.

Particular stress is laid on the novel arrangement of the pump cylinder and the novel arrangement of the valves, in that the valves can be renewed, when worn, without disturbing the pump cylinder in any way.

In Figures 2 and 3, I have illustrated a slightly modified form of jack, and in this form I provide a separate by-pass, or relief, passageway, which is distinct from the high pressure passageway.

Referring to these figures, it can be seen that the jack includes a base 50, having the axial recess 51 into which is threaded the ram cylinder 52. Surrounding the ram cylinder 52 is the reservoir cylinder 53 which is snugly fitted in the base.

Extending laterally from the base and at an angle thereto is the integral pump cylinder 54, which receives the pump plunger 55. Between the pump cylinder 54 and the axial recess 51, the base is provided with a valve recess 56, which opens out through the upper end of the base and

communicates with the interior of the reservoir cylinder 53.

Communicating with the valve recess 56 intermediate its ends is a diagonal passageway, or conduit, 57, and this passageway communicates with the lower end of the pump cylinder 54. Connecting the lower end of the valve recess 56 and the lower end of the ram cylinder is a high pressure passageway 58. Leading from the lower end of the ram cylinder is a relief passageway 59, and 10 extending upwardly from the passageway 59 is a second relief passageway 60, which leads above the valves for communication with the reservoir.

Flow of fluid through the relief passageways 59 and 60 is controlled by manually operated relief valve 61, which extends through a suitable packing gland 62 carried by the base.

Fitted within the valve recess 56 is a lower valve cage 63 in which is mounted a one-way opening ball valve 64. This cage 63 is held in place by the upper valve cage 65, which is threaded in the valve recess. This valve cage 65 also carries a one-way opening ball valve 66. The lower valve cage 63 has formed therein the longitudinal passageway 67 and a cross passageway 68 which communicates with the pump passageway, or conduit, 57.

This jack operates in exactly the same manner as that form of my jack previously described, but it is to be noted that when the relief valve is open, the fluid under pressure will travel through the passageways 59 and 60 back to the reservoir.

From the foregoing description, it can be seen that I have provided an exceptionally simple and durable form of jack, which will effectively accomplish the purpose intended.

Changes in details may be made without departing from the spirit or the scope of this invention, but what I claim as new is:—

1. A hydraulic jack comprising, a base having an enlarged cavity in its upper face and a smaller cavity at one side of the large cavity, a pump cylinder formed integral with the base and at one side of the cavities, a ram cylinder secured in the large cavity, a reservoir cylinder carried by the base and surrounding the ram cylinder and forming a reservoir in conjunction therewith, a ram slidably mounted in the ram cylinder, a pump plunger slidably mounted in the pump cylinder, the base having a passageway connecting the pump cylinder with the small cavity intermediate its ends, a passageway connecting the lower ends of the small and large cavities together, a one-way valve fitted in the small cavity below the first mentioned passageway, a second one-way opening valve detachably fitted in the small cavity and engaging the first valve, and means for by-passing fluid from the large cavity to the reservoir, said reservoir cylinder completely enclosing the upper end of the small cavity.

2. A hydraulic jack comprising, a base having an enlarged cavity in its upper face and a smaller cavity at one side of the large cavity, opening out said upper face, a pump cylinder formed integral with the base and at one side of the cavities, a ram cylinder secured in the large cavity, a reservoir cylinder carried by the base and surrounding the ram cylinder and forming a reservoir in conjunction therewith, a ram slidably mounted in the ram cylinder, a pump plunger slidably mounted in the pump cylinder, the base having a passageway connecting the pump cylinder with the small cavity intermediate its ends, a passageway connecting the lower ends of the small and

- large cavities together, a one-way valve fitted in the small cavity below the first mentioned passageway, a second one-way opening valve detachably fitted in the small cavity and engaging the first valve, and means for by-passing fluid from the large cavity to the reservoir, said means including a manually controlled valve, said reservoir cylinder overlying the upper end of the small cavity.
5. A hydraulic jack comprising, a base having a central large vertical recess formed in its upper face and a small vertical recess at one side thereof opening out said upper face, an integral pump cylinder formed on the base, a ram cylinder secured in the large recess, a reservoir cylinder carried by the base and surrounding the ram cylinder and forming a reservoir in conjunction therewith and overlying the upper end of the small recess, a ram slidably mounted in the ram cylinder, a pump plunger mounted in the pump cylinder, said base having a passageway connecting the lower end of the pump cylinder with the small recess intermediate its ends and formed from the interior of the pump cylinder, and a passageway connecting the lower ends of the small and large recesses together formed from the interior of the central recess, a valve cage removably fitted in the small, vertical recess having a longitudinal passageway therethrough and a cross passageway communicating with the first mentioned passageway in the base, a one-way opening valve controlling the flow of fluid through the cage, a second valve cage threaded in the small vertical recess against the first cage and having a one-way opening valve controlling the flow of fluid therethrough and means controlling the by-passing of fluid from the lower end of the ram cylinder to the reservoir.
3. A hydraulic jack comprising, a base having a central large recess in its upper face and a small recess in its upper face and opening out at one side of the large recess, an integral pump cylinder carried by the base, a ram cylinder secured in the large recess, a reservoir cylinder carried by the base and surrounding the ram cylinder and forming a reservoir in conjunction therewith, said reservoir cylinder enclosing the small recess, a pump plunger mounted in the pump cylinder, said
- base having a passageway connecting the rear end of the pump cylinder with the small recess intermediate its ends, and a passageway connecting the lower ends of the small and large recesses together, a valve cage fitted in the small recess having a longitudinally extending passageway and a cross passageway, a one-way opening valve controlling the flow of fluid through the cage, the first mentioned passageway in the base communicating with the cross passageway of the cage, a second valve cage detachably fitted in the recess against the first cage and having a one-way opening valve therein, said base also having relief passageways connecting the lower end of the large recess with the lower end of the reservoir, and a manually operated valve for controlling the flow of fluid through the relief passageways.
5. A hydraulic jack comprising, a base having a central large recess in its upper face and a small recess in its upper face opening out at one side of the large recess, an integral pump cylinder carried by the base, a ram cylinder secured in the large recess, a reservoir cylinder carried by the base and surrounding the ram cylinder and forming a reservoir in conjunction therewith, said reservoir cylinder enclosing the small recess, a pump plunger mounted in the pump cylinder, said base having a passageway connecting the rear end of the pump cylinder with the small recess intermediate its ends, and a passageway connecting the lower ends of the small and large recesses together, a valve cage fitted in the small recess having a longitudinally extending passageway and a cross passageway, a one-way opening valve controlling the flow of fluid through the cage, the first mentioned passageway in the base communicating with the cross passageway of the cage, a second valve cage detachably fitted in the recess against the first cage and having a one-way opening valve therein, said base also having relief passageways connecting the lower end of the large recess with the lower end of the reservoir, and a manually operated valve for controlling the flow of fluid through the relief passageways.
4. A hydraulic jack comprising, a base having a central large recess in its upper face and a small recess in its upper face and opening out at one side of the large recess, an integral pump cylinder carried by the base, a ram cylinder secured in the large recess, a reservoir cylinder carried by the base and surrounding the ram cylinder and forming a reservoir in conjunction therewith, said reservoir cylinder enclosing the small recess, a pump plunger mounted in the pump cylinder, said

JOSEPH J. MUELLER.
